UNITED STATES PATENT OFFICE.

EWALD J. SCHIFFKO, OF OAKLAND, CALIFORNIA, ASSIGNOR OF ONE-THIRD TO FRANK FRANZEN AND ONE-THIRD TO LUCILLE HILL, BOTH OF OAKLAND, CALIFORNIA.

PROTECTIVE APPARATUS.

Application filed September 1, 1925. Serial No. 53,960.

This invention relates to protective apparatus, and is particularly designed for the protection of banks, stores, treasuries or the like, when a hold-up is attempted on such 5 places.

The invention contemplates a door which may close the entrance to a bank, for example, and mechanism for closing the door. The mentioned mechanism is preferably 10 actuated by an authorized person at some distance from the mechanism which operates the door.

The invention further contemplates apparatus whereby one or more signals may be 15 actuated when the door operating mechanism is put into operation.

Another feature of the invention is the provision of means for locking the door, and means for unlocking the same, the unlocking 20 means being inaccessible to a person unauthorized to operate the unlocking mechanism.

Other features and objects will be apparent from the following specification.

25 The invention is illustrated in the drawings, in which

Figure 1 is a perspective view of part of a room from the interior thereof, this room being, for example, a banking room.

30 Figure 2 is an elevational view taken from the central vertical line of Figure 1 and looking toward the left.

Figure 3 is a sectional view taken on line 3-3 of Figure 2.

35 Figure 4 is a transverse section taken on the line 4-4 of Figure 3.

Figure 5 is a perspective view of a bar employed at the top of the door at the entrance to the room shown in Figure 1.

40 Figures 6 and 7 are perspective views of brackets employed in this invention.

Figure 8 is a perspective view of a bar employed in the door shown in Figure 1.

45 Figure 9 is an end view of the door, and

Figure 10 is a diagram of apparatus and

circuits employed in this invention.

Referring to the drawings for more detailed description, the numeral 12 indicates a door opening from the street into a vestibule 13. Entrance from the vestibule 13 into the room 14 may be had through the doorway 15. From the top of the doorway 15 is suspended a curtain 16 comprising chains 17 at the bottom of which is secured 55 a bar 18 shown in Figure 8, and having eyes

19 in its ends. Vertical rods 21 which extend from the top to the bottom of the doorway pass through the eyes 19 of the bar 18 which rests on brackets 22 shown in Figure 7.

The vertical rods 21 and the ends of the horizontal rod 18 are inside the inner edges 23 of the doorway 15. The bar 18 is slideable on the vertical rods 21, and since the curtain 16 is made up mostly of a series of vertical chains, the curtain may be collapsed when the door 25 is pushed upwards as may sometimes occur as hereinafter explained. Below the curtain 16 a vertically movable collapsible door 25 is located. The door 25 comprises an upper member 26 extending between the inner sides 23 of the doorway 15. To the underside of the member 26 is secured a rod 28 shown in Figure 5. The rod 28 has eyelets 29 at the ends thereof and apertured guide members 30 near the ends. The rod 28 also has at one end thereof a member 31, the function of which will hereinafter be explained. The rod 28 is slideable on the vertical rods 21 which pass through the members 30 of the rod 28.

A series of chains 33 are secured to the bar 28. These chains make the door collapsible. The door also comprises horizontal bars 35, 36 and 37. To the eyelets 29 of the bar 28 are secured chains or cables 39 which extend upwardly and pass over pulleys 40 and then pass downwardly and are secured to members 41 turnable with shaft 42 which is coupled at one end to an electric motor 43 shown, in Figure 1, as positioned alongside one end of the vestibule. The lower end of the collapsible door is secured as shown at 44 and 45 to members 46 and 47 which are raised above the floor 48 and constitute the bottom of the doorway. When the motor is actuated, it turns the shaft 42 on which ratchets 49 are secured. As the shaft 42 is rotated, the chains or cables 39 are wound around the members 41, best shown in Figure 4, and such action raises the bar 28 and the door attached thereto since the cables 39 are secured to the eyelets 29 of the bar 28. As the shaft 42 rotates, pivoted dogs 50 engage the ratchets 49 and thus prevent the door from falling down. When the door is fully raised, the top of it is in contact with the bottom of the chain curtain 16. As the top of the door reaches its uppermost position, 110

which is just under the bar 18 of the curtain 16, the member 31, which is positioned at one end of the bar 18 and best shown in Figure 3, moves a pivot switch 52 and opens 5 the circuit of the motor 43. As stated the dogs 50 lock the door by engagement with the ratchet wheels 49.

Apparatus is provided to unlock the door and such apparatus comprises a cable 53 secured to the dogs at points 54. The cable 10 53 passes upwardly and over sheaves 55 to a point 56 outside of the building. The position 56 is so high that it may not be reached without a ladder or similar means. 15 By pulling outwardly on the cable 55 at the point 56, the dogs 50 may be made to disengage the ratchet wheels 49 and thus unlock the door. When the door is unlocked, it will fall and collapse of its own weight until 20 the member 26 falls within the members 46 and 47 and rests on projections 58 and 59 of the members 46 and 47 respectively, as shown in Figure 2. The chains 33 of the door 25 will then lie in collapsed position between the members 46 and 47. In order to 25 close the motor circuit opened by the pivot switch 52, the cable 61 is secured to the switch 52 and extends outwardly to a point 63 adjacent the point 56 on the outside of the building.

Referring now to figure 10, the numeral 65 indicates an annunciator which may be placed in any desired location. Numeral 66 indicates an electrically operated bell which 30 is preferably placed on the outside of the building in order to give an alarm, and the numeral 67 indicates a lamp which is part of the alarm. The numeral 68 indicates a battery for operating the annunciator, bell and 35 lamp. The numerals 69, 70 and 71 designate switches which, in case the apparatus of this invention is installed in a bank, may be in tellers' cages. A line 72 leads from a source of power to one terminal of the motor 43, 40 the other terminal of which is connected by wire 73 to the lower terminal of the switch 69. Wires 74 and 75 lead off from the wire or conductor 73 to the lower terminals of the switches 70 and 71 respectively. The lower

terminals of the switches 69, 70 and 71 are 50 connected by means of a conductor 76 to one terminal of the battery 68. The upper terminals of the switches 69, 70 and 71 are connected by means of a conductor 77 to the other terminal of the source of power which 55 operates the motor. The upper terminals of the switches 69, 70 and 71 are connected respectively by conductors 78, 79 and 80 with the annunciator 65. A conductor 81 connects the annunciator 65 with the bell 66. A conductor 82 connects the bell 66 with the lamp 67 and a conductor 83 connects the lamp with the battery 68.

When an attempt is made to hold-up a teller in order to obtain money from him, 65 the teller may close the switch as, for example, the switch 69 which is within his cage and which may be adapted to be operated by the foot of the teller. The closing of the switch 69 closes the power circuit so 70 that the motor is actuated and the shaft 42 is rotated, whereupon the door is raised thus closing the exit and preventing the escape of the person who attempts to hold-up the teller.

From the diagram in Figure 10, it will also be seen that the closing of the switch 69 closes the alarm circuit so that the annunciator 65, the bell 66 and the lamp 67 are actuated.

I claim:

In a device of the type described, a door frame having a recess at the bottom thereof for receiving a collapsible door, a cover for the top of said recess which normally forms the door sill, a collapsible door connected to said door sill, means for raising said door sill for causing said door to close the door opening, said means including a shaft mounted in said recess, a ratchet carried by 90 said shaft and a pawl for engaging with said ratchet, said collapsible door being formed of chains that are shaped in a Y at the lower end thereof and secured to the sides of the walls forming the recess whereby 95 the actuating mechanism disposed within said recess is protected.

EWALD J. SCHIFFKO.
